UNITED STATES PATENT OFFICE.

MICHAEL O'HARA, OF BROOKLYN, NEW YORK.

SOAP MANUFACTURE.

SPECIFICATION forming part of Letters Patent No. 394,660, dated December 18, 1888.

Application filed March 31, 1888. Serial No. 269,051. (No specimens.)

To all whom it may concern:

Be it known that I, MICHAEL O'HARA, of Brooklyn, Kings county, in the State of New York, soap-boiler, have invented a certain 5 new and useful Improvement in the Manufacture of Soap, of which the following is a specification.

I produce a pure and practically neutral soap having all the qualities of toilet and 10 laundry soap at a moderate price, and without the admixture of rosin, sal-soda, starch, soapstone, or other injurious ingredients.

I boil palm-nut oil or cocoanut-oil with a strong lye of caustic soda until it saponifies. 15 Then, with further boiling, I add strong lye, subsequently add linseed-oil or cotton-seed oil, again add strong lye, afterward add bleached palm-oil or tallow, then salt, and allow it to stand eight or ten hours perfectly 20 quiet. A considerable quantity of impure water strongly saturated with salt collects at the bottom. This is pumped out or otherwise removed and may be thrown away. I have found no use for this which will make it worth 25 preserving. Next I add strong lye and oil, allow it to stand again a few hours, and again pump or otherwise take away the watery stratum from the bottom. This time the fluid which settles to the bottom will contain much 30 salt, but it will be so strong with alkali that it is valuable to preserve for future use. This salt lye can be used for the next lot, instead of dry salt, or it may be introduced at any stage where I have above described strong 35 lye. Having ready in a separate vessel a strong solution of slicate of soda, this is run into the kettle and boiled, then add by sprinkling a strong solution of ultra-marine blue or Venetian red, or both, and cool in frames, and 40 cut up into bars or otherwise shape for market. I will repeat, designating approximately the quantities.

The operation should be modified somewhat, according to the judgment of the attendant, some lots of materials acting differently from others and requiring corresponding variations in the quantities, but with ordinarily-pure materials the quantities should be about as follows:

45 Add to three thousand pounds of palm-nut oil or cocoanut-oil four hundred gallons of caustic-soda lye at about 30° Baumé and boil

together until they saponify. Continue the boiling and gradually add strong lye at about 55 30° Baumé until the mass curds, preferably separating into pieces about the size of Indian corn. Continue the boiling and gradually add linseed-oil or cotton-seed oil, three thousand pounds, (more or less,) until the soap closes again. Next add more strong lye, about 60 30° Baumé, and boil until the mass curds. Then add three thousand pounds of beef tallow or bleached palm-oil and boil until it closes again. At this stage add salt, either all dry or partly 65 in the form of a solution or brine of alkali reserved from a previous lot, and boil until the soap curds again. Then it is allowed to stand eight or ten hours, and the water which collects in a stratum at the bottom is pumped or drained off and rejected. The temperature at 70 this stage is important. It will suffice to simply shut off the steam or extinguish the fire if it has been heated by a direct fire and allow it to stand at about the boiling temperature. Now add four hundred gallons of strong lye, 75 about 30° Baumé, and boil with open steam for eight hours, and let it stand again partially cooled or at about the boiling temperature eight or ten hours. Again pump out or otherwise remove the material from the bottom, 80 which will be a strong solution of caustic soda and salt. It will contain much salt. This should be preserved for future use with another lot. Provide in a separate vessel a solution of eight hundred pounds (more or less) 85 of silicate of soda in four hundred gallons of water. Run this into the kettle and boil again. It will close together at this point. Continue boiling until dry. Then for coloring, having made a solution of fourteen pounds 90 of ultramarine-blue and four pounds of Venetian red in three gallons of water, or using more or less of either according to the color desired, I add this by gently sprinkling while the soap is boiling. Then draw off into frames, 95 cool, and cut up into bars.

The process above described effects complete saponification of the cocoanut-oil or palm-nut oil.

By the above-described process of first saponifying the difficult oil with a large percentage of alkali, and then after true saponification is effected adding other ordinary fats, I am able to make a nearly neutral soap with 100

the palm-nut oil or cocoanut-oil, retaining its saponified condition.

By the large admixture of silicate of soda and water I am able to produce the requisite bulk and to make a soap which is efficient and cheap.

By the peculiar construction of the kettle I am able to boil with fire and steam together, or either separately, and to drain the brine or other product from the extreme bottom.

The accompanying drawing forms a part of this specification and is a vertical section through the boiler.

Referring to the figure, A is the main body of the boiler, and A' a sub-chamber of smaller diameter extending down into the furnace.

C is brick-work, and c a grate.

B is a coil of pipe adapted for heating by steam. It is located a proper distance from the bottom of the main chamber A, and is provided with connections for supplying steam and discharging the water produced by condensation.

D is a smaller coil provided with connections for supplying steam and discharging the water of condensation.

E is a pipe connecting with the bottom of the sub-chamber A' and leading out across the furnace, controlled by a cock or valve, E'.

In the use of the apparatus the material is introduced in the kettle, filling the main chamber A and the sub-chamber A', and is boiled both by steam supplied in the coils B and D, and also by fire on the grate c.

The entire process in the kettle under ordinary conditions requires four (4) days. Then the soap should usually stand in the frames before cutting eight (8) days more. Total, twelve (12) days.

I do not in this patent claim the apparatus; nor do I claim the addition of easily-saponifiable fat without further alkali after the difficult fat has been saponified. Such are made the subjects of separate applications for patent, one filed March 31, 1888, Serial No. 269,050, and one filed October 25, 1887, Serial No. 253,301.

I claim as my invention—

1. In the manufacture of soap, the method described of combining palm-nut oil or analogous fat difficult of saponification with strong lye to constitute soap and subsequently adding lye to curd it, and then adding linseed-

oil or analogous oil which is easily saponified, and boiling until the soap again closes, as herein specified.

2. In the manufacture of soap, the method described of combining palm-nut oil or analogous fat difficult of saponification with strong lye to constitute soap and subsequently adding lye to curd it, then adding linseed-oil or analogous oil which is easily saponified, and boiling until the soap again closes, then adding further lye until the soap again curds, then adding tallow or other easily-saponifiable fat, and a third time inducing the closing of the soap, as herein specified.

3. In the manufacture of soap, the method described of combining palm-nut oil or analogous fat difficult of saponification with strong lye to constitute soap and subsequently adding lye to curd it, then adding linseed-oil or analogous oil which is easily saponified and again inducing the closing of the soap, then adding further lye until the soap again curds, then adding tallow or other easily-saponifiable fat, and a third time inducing the soap to close, then adding salt and decanting, then adding lye and again decanting, and subsequently boiling until the mass again closes, substantially as herein specified.

4. The manufacture of a neutral or nearly neutral soap with a large proportion of palm-nut oil or analogous fat difficult of saponification by first saponifying the same with an excess of alkali, then twice curding and closing the soap by successive additions first of lye to curd and then of a proper quantity of an easily-saponifiable fat to close, then curding with salt, then decanting and removing such watery matter as is readily separable, then boiling with an excess of lye, and again decanting and removing the watery matter, after which the soap is closed by boiling with silicate of soda, and may be colored, cooled, and cut for use, all substantially as herein specified.

In testimony whereof I have hereunto set my hand, at New York city, New York, this 30th day of March, 1888, in the presence of two subscribing witnesses.

MICHAEL O'HARA.
